Inventor,

Ellen Hammond Putrell,

By Thos. Ahlmann

Attorney

UNITED STATES PATENT OFFICE

ELLEN HAMMOND FUTRELL, OF NEW YORK, N. Y.

MANICURE INSTRUMENT

Application filed September 20, 1929. Serial No. 393,969.

This invention relates to manicure instruments, and particularly to a device of the character adapted for use in treating cuticle by the displacement of said cuticle without liability of injuring the same, the said device being somewhat yielding in character, although having sufficient rigidity to perform the necessary functions. Preferably, the body of the instrument is formed of composition with a rubber base, although the inventor does not wish to be limited with respect to this feature in its production, but in practice it has been found that rubber slightly harder than that of the ordinary pencil erasers is satisfactory.

It is furthermore an object of the invention to produce a device of the character having an end shaped to act or operate as a finger nail cleaner, accomplished by manipulating the device under the nails from whence deposits will be removed; and the inventor furthermore contemplates the production of a device of the character for reinforcing the body and providing a nail file, the said device being comparatively inexpensive to manufacture and efficient and satisfactory in use.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a view in perspective of a manicuring instrument embodying the invention;

Figure 2 illustrates a plan view thereof;

Figure 3 illustrates a transverse sectional view; and

Figure 4 illustrates an edge elevation.

45 In these drawings 5 denotes the body of

the instrument being at one end tapered, as at 6, and preferably the end edge is outwardly curved, although it obviously may be straight or concave. The opposite end 7 of the body has its edges tapered and the surfaces at angles thereto are also tapered in order that the tip 8 may be relatively narrow and thin, in fact, the tip is nearly pointed and this construction facilitates the application of the device when inserted under the nail.

50 The body of the device is preferably reinforced by employing plates 9 and 10 fastened in place by securing devices 11 and 12 in the nature of rivets or the like, and the fastening 12 also acts as a pivot on which a blade 13 is oscillative in order that it may be moved to a position parallel with the plate 10, or at positions at angles thereto, as indicated by dotted line, Fig. 2. The surface of the blade 55 may be serrated or otherwise roughened, as shown at 14, to produce a filing surface which will serve to dress the nails.

60 The efficiency of the instrument may be augmented by dipping the blunt end in soapy water and manipulating it in contact with the cuticle where cuticle deposits remaining after the cuticle has been displaced may be effectively removed.

65 It is to be understood that the proportions of the commercial product may be changed to suit conditions, and the inventor does not wish to be limited with respect to these features.

I claim:

1. In a manicure instrument, a body of 70 slightly yielding material having tapered ends, one of said ends being shaped to act as a cuticle pusher for the base of the nails, the other of said ends being shaped to act as a nail cleaner whereby deposits between the 75 nails and fingers can be removed, reinforcing plates secured on the said member, and an abrading blade pivotally secured on one of said plates.

80 2. In a manicure instrument comprising an 85

elongated body of slightly yielding material having one end tapered to an edge adapted to engage cuticle for displacing the same, the other of said ends being substantially pointed and reduced in thickness to be inserted in the spaces between the nails and the fingers for displacing foreign substances, and reinforcing plates secured on the sides of the said member extending longitudinally of the said body beyond the longitudinal center toward each end.

ELLEN HAMMOND FUTRELL.
